UNITED STATES PATENT OFFICE

JOHN F. SCHMIDT, OF CINCINNATI, OHIO, ASSIGNOR TO THE CORCORAN-BROWN LAMP COMPANY, OF CINCINNATI, OHIO, A CORPORATION OF OHIO

LAMINATED LAMP CONSTRUCTION

Application filed May 29, 1930. Serial No. 457,410.

This invention relates to an improvement in the construction or formation of lamp reflectors and bodies and has for an object to produce a cheaper construction than has been produced heretofore, without in any manner sacrificing beauty, strength, or ease of manufacture.

In fact, an object of my invention is to so construct lamp bodies and reflectors that a material gain is made in the actual strength of such elements and a corresponding gain made in the character of the finished surface of the lamp elements.

I accomplish the objects which have been set forth, by laminating construction, which, generally speaking, is not broadly new. I am well aware that the idea of laminating lamp body and reflector elements, has been practiced to a more or less degree commercially, heretofore, and that such attempts as have been made along this line, have resulted to an immaterial degree in attaining the economical results which had been hoped for them. Hence, I do not attempt to attain results such as have been described herein, except in the specific manner I will set forth and which the appended claims specifically relate.

In the drawing which I have chosen as illustrative of the ideas I describe herein, I have illustrated forms of lamp elements in somewhat embrionic, generic or diagrammatic condition, in order that my invention may be the more readily understood, regardless of the refinements, finishing touches, or variations of shape or design to which it may be applied. Therefore:

Fig. 1 shows a typical lamp reflector in section, formed in accordance with my invention.

Fig. 2 is a front elevation of the reflector shown in Fig. 1.

Fig. 3 is a rear elevation of the reflector shown in Fig. 1.

Fig. 4 is a sectional elevation of a lamp body constructed in accordance with my invention.

Fig. 5 is a rear elevation of the lamp body shown in Fig. 4.

Fig. 6 is a front elevation of the lamp body shown in Fig. 4.

Fig. 7 is a rear elevation of the lamp body shown in Fig. 4, with the outer lamina of metal removed in order to disclose the inner or core lamina.

As exemplary of the invention I have made, I have chosen to refer, by way of the most commonly used of metals for lamp construction purposes, to steel and brass. In order that these metals may be most easily recognized in the various views of the drawing, I have shown all brass laminæ by vertical shade lines, while steel laminæ have been shown by horizontal shade lines.

In such a structure as the exemplary reflector shown in Figs. 1, 2 and 3, there have been shown but two laminæ. The outside lamina which is of steel, as shown by horizontal lines in Fig. 3, is preferably much thicker than the inner lamina which, as shown in Figs. 1 and 2, is of brass. The thought of the relative thicknesses of these laminæ is conveyed by the metal thickness sections shown in Fig. 1, as well as in the distances between the concentric circles in Fig. 2, but, in no manner is this intended to show actual or even approximate relative differences, being merely intended to render my invention more clearly understood as to this feature.

Now, there is another feature of importance connected with my invention. This consists in so assembling the laminæ of my invention that the grain of the metal occupies crossed relation to each other. The purpose of such a crossed assembly of laminæ is two-fold. First, the crossing of the laminæ produces a strengthening effect on the entire reflector, which renders it less liable to become distorted through warpage of its reflector from circular to elliptical shape. Second, the crossing of the superposed laminæ with each other, produces an improved and smoother optical effect because the grain lines in the thin inner lamina are supported, with better results, against the formation of wave lines in the finished or reflecting surface of the inner lamina, as would create spotty,

zoned, or wavy variations in the light pattern projected by the reflector.

I have referred, in this general statement, to the fact that I have chosen to make the 5 lamina which is to be highly finished, of a thickness which is less than that of the outer lamina. This statement may be amplified or enlarged upon to develop another feature of my invention. This consists in describing 10 the precise thickness which I have found to be necessary to an embodiment of my invention. Briefly, but comprehensively stated, the thickness of the lamina which is the highly finished or reflecting agency, must be 15 such as, when drawn, pressed or spun into laminated relation, will neither tear nor buckle. With this comprehension of this part of my invention, it is well to point out that in the use of different metals the thickness 20 of the metal of the lamina which is to be used for the highly finished reflecting surface will naturally vary. This is occasioned because some metals draw much more readily than others without tearing or buckling, 25 as well as because some metals are much softer than others and have less grain structure than others. In other words, the purpose of such a provision in my invention is to provide a lamina of metal for high surface 30 finish purposes, which will be as thin as possible to permit of spinning, drawing or pressing within or over the heavier metal shell without danger of tearing, and yet not so thick as would result in a buckling of the 35 metal thereof, with a consequent distortion of light beam pattern and other trouble such as would be occasioned when closely related laminae are caused to separate because of lack of adhesion between them.

40 In connection with this feature of adhesion between the laminae, I contemplate the retention of the laminae in properly assembled relation, in various ways. I have found that there are various ways of causing the 45 adhesion of the laminae, among which may be mentioned cementing, electrolytic adhesion, plating, amalgamation, or the union produced by curling the edges, piercing, crimping or otherwise mechanically accomplishing this result. In any event, such 50 means of adhesion as may be employed, is subject, to some extent, to the thinness of the metal of the highly finished lamina, as well as to the physical 55 characteristics governing the manner of its use, it being carried in mind that one of the desirable features of my invention is to produce as cheap a structure as possible by the use of as thin a lamina as is practical for the highly finished surface of the structure, consistent with the character of the metal being worked or the design of the structure.

In Figs. 4, 5, 6 and 7 I have shown such a 60 structure as is contemplated by me in the

building of a lamp which employs a body and reflector of one piece, in which the inside surface is highly finished for reflecting purposes, and in which the outside surface is highly finished in the same manner, for purposes of 70 beauty and protection from deterioration. A lamp structure of this construction, is quite readily adapted to large lamps of the flood light type, in that marked simplicity of construction, strength, relatively inexpensive 75 cost of manufacture, efficiency of light projection, beauty of finish, and ability to withstand weather conditions, are attained in such a laminated single shell construction. This lamp is produced by providing a laminated 80 structure having a relatively thick core of steel or other inexpensive metal, which is covered, both inside and outside, with relatively thin metal laminae which are weather 85 resistant and capable of receiving the high 90 finish required of a reflecting surface as well as an exterior surface of beauty. Figs. 4, 5 and 6 show that the inner and outer laminae of such a lamp construction are of the higher value metal, while Fig. 7, which is a rear elevation and shows the outer lamina removed, shows the core to be of the less expensive and stronger core metal.

Of course, in as much as the illustrated disclosure is merely intended to be exemplary, for the purposes of setting forth the principles of my invention as above described, I have not gone into a description of such details as the commonly employed doors or closures, with their attendant attachments, 95 fastening devices, lamp bulb mountings, focusing devices, brackets, etc.

Among the advantages of my construction, several of which have been mentioned above, there is a marked improvement obtained through the effect produced in the rapid radiation of heat from a lamp so constructed. This is of marked advantage in such lamps as are used for flood lighting, where a powerful light beam is employed, 105 with the consequent expenditure of much energy which is dissipated in the form of heat. In flood lamps employing an air space between the body shell and reflector, this heat is trapped and is quite likely to result in burned 110 insulation as well as destruction of the surface finish of the reflector and body through 115 discoloration and peeling.

I have mentioned the tearing of the surface metal laminae should the gauge of the 120 metal be too thin to prevent this damage. It is not only tearing that is to be avoided but also the possibility of stretching the metal to the point of opening the grain and causing it to break down by becoming porous to 125 the point where it is not possible to produce a beautiful and optically perfect surface finish. Therefore, it is essential that the thinness of the metal of the surface laminae be such that this consideration of grain struc- 130

ture enlargement be considered as well as that of metal tearing.

Having thus described my invention, what I claim is:

- 5 1. A lamp construction comprising a hollow laminated structure having a core and a thinner lamina, the grain of the laminae being crossed relatively to each other.
- 10 2. A lamp construction comprising a hollow laminated structure having a core of relatively stiff material, and a thinner lamina of more ductile material, the grain of the laminae being crossed relatively to each other.
- 15 3. A lamp construction comprising a hollow laminated structure having a core of relatively stiff material, and a lamina of thinner and relatively more ductile material, the grain of the laminae being crossed relatively to each other, with the thickness of the thinner lamina such that it will neither tear nor buckle when drawn, pressed or spun into position with the first mentioned lamina.
- 20 4. A laminated lamp structure comprising a core and thinner laminae covering the core surfaces, the grain of the laminae crossing each other.
- 25 5. A laminated lamp structure comprising a core of relatively stiff metal, and thinner laminae of more ductile metal covering the core surfaces, the grain of the laminae being crossed relatively to each other.
- 30 6. A laminated lamp structure having a core of relatively stiff metal, and laminae of thinner and relatively more ductile metal covering the core surfaces, the grain of the laminae being crossed relatively to each other, with the surface laminae of such thickness that they will neither tear nor buckle when drawn, pressed or spun into position with the first mentioned lamina.
- 35 7. A laminated lamp structure having a core of relatively stiff metal, and laminae of thinner and relatively more ductile metal covering the core surfaces, the grain of the laminae being crossed relatively to each other, with the thickness of the thinner laminae such that they will neither tear nor buckle when drawn, pressed or spun into position with the first mentioned lamina.
- 40 50 In testimony whereof I hereunto affix my signature.

JOHN F. SCHMIDT.
